UNITED STATES PATENT OFFICE.

ARTHUR B. BELLOW'S, OF PITTSBURG, PENNSYLVANIA.

TRUCK-BOLSTER.

SPECIFICATION forming part of Letters Patent No. 693,220, dated February 11, 1902.

Application filed November 9, 1901. Serial No. 81,670. (No model.)

To all whom it may concern:

Be it known that I, ARTHUR B. BELLOW'S, of Pittsburgh, Allegheny county, Pennsylvania, have invented a new and useful Truck-Bolster, of which the following is a full, clear, and exact description, reference being had to the accompanying drawings, forming part of this specification, in which—

Figure 1 is a partial transverse section on the line II of Fig. 2 looking toward the left. Fig. 2 is an end elevation showing one form of my improved bolster in place, the side portions of the truck being broken away. Fig. 3 is a partial top plan view of my improved bolster. Fig. 4 is an end perspective view showing the cutting away of the I-beam flanges, and Figs. 5, 6, and 7 are detail views of a modified form.

My invention relates to truck-bolsters for railway-cars, and is designed to afford a simple and strong construction which can be easily and cheaply made from commercial I-beams or channels.

In forming my improved bolster with I-beams, as shown in Figs. 1 to 4, I provide two beams 2, which are placed in parallelism and properly secured together. Each of the I-beams at its ends is shaped as shown in Fig. 4—that is, each of the lower flanges 3' is cut away for a suitable distance from the end, while the outer top flange 4 is similarly cut away an equal distance. Vertical angle-bars 5 are then riveted to the webs of the I-beams in the position shown in Fig. 3, these angles having their projecting flanges preferably beveled at their lower ends, as shown at 6 in Fig. 2. In this figure, 7 indicates the inverted-arch bar, 8 the spring-plank channel-iron, and 9 the coiled springs for the bolster. These springs bear at their upper end upon the spring-bearing seat 10, which is secured between the ends of the I-beams, preferably by the same rivets that secure the angles 5 in place, together with additional rivets, through flanges 10' of the seat. The bolster guide-bars 11 extend vertically between the angles 5 and the end portions of

the I-beam flanges 3 and 4, of which the flanges 3 are preferably cut on a bevel, as shown in Fig. 3. The I-beams of the bolster are secured together between its end portions by plate 12, 13 being the truck center-plate and 14 a reinforcing-plate for the central part of the bolster.

In Figs. 5 to 7, inclusive, I show a construction wherein two channels 2' are employed with outwardly-turned flanges 4', both of which are cut away at their ends. The angle-bar guides 5' are used as before.

The advantages of my invention result from the peculiar manner of forming the truck-bolster body, since a strong construction is afforded which can be easily and cheaply made from commercial flanged shapes, such as channels or I-beams.

I claim—

1. A truck-bolster having its body formed of flanged rolled shapes, the exterior flanges being cut away from the ends of the shapes, and exterior vertical guides secured to the webs of the shapes at the cut-away portions; substantially as described.

2. A truck-bolster body formed of two I-beams with their exterior flanges cut back from the ends and exterior vertical guides secured at the cut-away portions, the inner lower flanges also being cut away, and a spring-bearing seat secured between the ends of the shapes; substantially as described.

3. A truck-bolster comprising a pair of I-beams connected by a bottom plate, the outer flanges of said beams being cut away at their end portions, vertically-extending angles secured to the end portions of the web, the inner lower flanges being cut away at the ends, and a spring-bearing seat secured between the end portions of the webs; substantially as described.

In testimony whereof I have hereunto set my hand.

ARTHUR B. BELLOW'S.
